UNITED STATES PATENT OFFICE

112,737

DESIGN FOR A MINIATURE HURDY GURDY CABINET

Harry Goldman, Chicago, Ill.

Application January 22, 1938, Serial No. 74,490

Term of patent 3½ years

To all whom it may concern:

Be it known that I, Harry Goldman, a citizen of the United States, residing at Chicago, in the county of Cook and State of Illinois, have invented a new, original, and ornamental Design for a Miniature Hurdy Gurdy Cabinet, of which the following is a specification, reference being had to the accompanying drawing, forming part thereof.

The figure is a perspective view of a miniature

hurdy gurdy cabinet showing my new design. The cabinet end at the right (not shown) is the same as the cabinet end at the left which is shown in the drawing. The dominant features of my design reside in the grille shown at the front of the cabinet.

I claim:

The ornamental design for a miniature hurdy gurdy cabinet, as shown and described.

HARRY GOLDMAN.
